(57) **CLAIM**

The ornamental design for a handwriting instrument, as shown and described.

DESCRIPTION

FIG. 1 is a perspective view of the top, front and left side of a handwriting instrument showing my new design.

FIG. 2 is a perspective view of the bottom, front and right side thereof.

FIG. 3 is a left side view thereof.

FIG. 4 is a front view thereof.

FIG. 5 is a back view thereof.

FIG. 6 is a top view thereof, enlarged in relation to the other figures.

FIG. 7 is a perspective view of the top and front thereof.

FIG. 8 is a perspective view of the bottom and front thereof.

FIG. 9 is a perspective view of the top, front and left side thereof, shown with the nib extended.

FIG. 10 is a perspective view of the bottom, front and right side thereof, shown with the nib extended.

FIG. 11 is a left side view thereof, shown with the nib extended.

FIG. 12 is a front view thereof, shown the nib extended; and, FIG. 13 is a bottom view thereof, enlarged in relation to the other figures.
